CLAIM

The ornamental design for a watchband for smart watch, as shown and described.

DESCRIPTION

FIG. 1 is a perspective view of a watchband for smart watch; FIG. 2 is another perspective view thereof; FIG. 3 is a front elevational view thereof; FIG. 4 is a rear elevational view thereof; FIG. 5 is a left side elevational view thereof; FIG. 6 is a right side elevational view thereof; FIG. 7 is an enlarged top plan view thereof; FIG. 8 is an enlarged bottom plan view thereof; FIG. 9 is a reference front perspective view thereof, shown in use; and, FIG. 10 is a reference rear perspective view thereof, shown in use.

The broken lines in the drawings depict portions of the watchband for smart watch that form no part of the claimed design.
